<https://www.kohls.com/product/prd-2990556/oxo-stronghold-suction-corner-basket.jsp> (Year: 2017).*Primary Examiner — David G Muller
Assistant Examiner — Nathan M Johnston(57) **CLAIM**

The ornamental design for a suction basket, as shown, and described.

DESCRIPTION

FIG. 1 is a perspective view of the suction basket showing our new design;

FIG. 2 is a front elevation view thereof;

FIG. 3 is a rear elevation view thereof;

FIG. 4 is a side elevation view thereof;

FIG. 5 is a top plan view thereof; and,

FIG. 6 is a bottom plan view thereof.

The broken lines depict environment and form no part of the claimed design.
